UNITED STATES PATENT OFFICE.

ALBERT DÖRING, OF DRESDEN, GERMANY.

REVOLVING-HOOK SEWING-MACHINE.

SPECIFICATION forming part of Letters Patent No. 657,525, dated September 11, 1900.

Application filed September 22, 1898. Serial No. 691,639. (No model.)

To all whom it may concern:

Be it known that I, ALBERT DÖRING, a subject of the King of Saxony, residing at Dresden, Kingdom of Saxony, Germany, have invented certain new and useful Improvements 5 in Sewing-Machines, of which the following is a specification.

The invention consists in the features and combinations of features hereinafter described, and particularly pointed out in the claim.

In the drawings, Figure 1 is a side view, and Fig. 2 a plan view, of the invention. Fig. 3 is a perspective view of parts of Fig. 1, and 15 Fig. 4 is a perspective view of the thread-looper.

The subject of the present invention concerns an improvement in sewing-machines in which the looper is independent of the bobbin-case.

The subject-matter of the invention consists in that the bobbin-case obtains individually an oscillating or rocking movement for the purpose of accelerating the guiding of the bobbin-case through the thread-looper and to loosen or tighten the bobbin-thread at the proper moment. The whole device is arranged beneath the base-plate of the sewing-machine. 20

a is a stirrup.

25 *b* is a bracket supported in the stirrup *a* and adapted to oscillate, the connection between the part *b* and the stirrup consisting of a reduced portion or pintle fitting an opening in the stirrup. A link *c* is connected to the part *b*, and the upper end of this link is forked, as shown in Fig. 2, to embrace a cam *e⁰*, which is mounted on a shaft *d*, passing through the stirrup. The cam *e⁰* is fixed to a vibrating looper *e* of crank form having a horizontal 30 arm adapted to seize, hold, and guide the loop of needle-thread. The loop is seized by the point *e'*, held by the guide *e²*, and on further movement the loop is allowed to glide off the rear part *e³*, Fig. 4, being held open and 35 guided over the bobbin-case *f*. The looper operates around the said bobbin-case, which is arranged in a holder hinged to the part *b*.

A cymbal-shaped case *g* is rigidly secured to the part *b*, Fig. 3.

The holder comprises a cylinder *h*, pivotally 50 connected to the part *b* at *i* and held in position by the part *k*. The cylinder *h* has a handle *l*, by which it may be moved toward and from the part *g*, and on said handle a lever *m* is pivoted, which operates a spring-bolt *n*, so 55 that said bolt may be projected into the eye of the bobbin, and thus prevent the bobbin-case from falling down when the cylinder *h* is swung back, as shown in Fig. 3. On the periphery of the cylinder *h* is arranged the 60 needle-guard *o*, which prevents contact of the looper-point with the needle. A nose-piece *p*, at the bottom of the cylinder inside thereof, and at the side a light flat spring *q* are provided for the purpose of supporting the bobbin-case. A spring *r* on the case *g* also serves 65 to support the bobbin-case.

In operation when the shaft *d* is rocked the looper *e* receives an oscillating motion and the point *e'* seizes the loop of needle-thread, 70 so that on further movement of the looper the loop of thread is expanded and glides from the rear part *e³* over the bobbin-case. At the same time the part carrying the bobbin-case receives a reciprocating motion from the cam 75 *e⁰* and the bracket *b*, which motion effects the loosening and retightening of the bobbin-thread.

I claim—

In combination in a sewing-machine, a 80 thread-looper comprising an oscillating arm, a shaft carrying said arm, a cam on said shaft, a bobbin-case holder, means for oscillating said holder in a direction transversely of the end of the looper-shaft, said means comprising a pivoted stirrup *b* having a link engaging and oscillated by the cam of the looper-arm substantially as described.

In witness whereof I have hereunto set my hand in presence of two witnesses.

ALBERT DÖRING.

Witnesses:

HERNANDO DE SOTO,
PAUL ARRAS.
